UNITED STATES PATENT OFFICE.

BEN K. FORD, OF OAK PARK, ILLINOIS, ASSIGNOR TO AMERICAN CAN COMPANY, OF NEW YORK, N. Y., A CORPORATION OF NEW JERSEY.

SHELLAC-PACKAGE.

1,173,257.

Specification of Letters Patent. Patented Feb. 29, 1916.

Application filed September 14, 1914. Serial No. 861,555.

To all whom it may concern:

Be it known that I, BEN K. FORD, a citizen of the United States, residing in Oak Park, in the county of Cook and State of Illinois, have invented a new and useful Improvement 5 in Shellac-Packages, of which the following is a specification.

My invention relates to shellac packages, providing for the packaging and shipping 10 of liquid orange shellac and similar substances.

The ordinary sheet metal vessel or can used to market liquids is composed of tin, or more accurately a very thin sheet of iron 15 covered on both sides with tin. Considerable annoyance and loss has resulted from the use of vessels of this sort for the packaging of liquid orange shellac and certain other liquids which have been found to be 20 affected by contact with the tin coating for prolonged periods. Where liquid orange shellac is package in tin containers it has been found to lose its attractive orange color and to turn a dirty, muddy brown if left in 25 the container for the time necessary to place it in the hands of the ultimate consumer.

It is the principal object of this invention to provide a shellac and equivalent package for the packaging and marketing of liquid 30 orange shellac and the like in which the contents may be left for an indefinite period without appreciable effect upon it.

Other objects and advantages of the invention will be apparent as it is better understood from the following description when considered in connection with the accompanying drawing illustrating a preferred embodiment thereof.

Referring to the drawing, Figure 1 is a 40 side elevation of a container or vessel embodying my invention; Fig. 2 is a vertical sectional view taken substantially on the axis of the container shown in Fig. 1; and Fig. 3 is an enlarged partial sectional view 45 taken substantially on the line 3—3 of Fig. 1.

The container shown on the drawing is of a usual and well known type and consists of side walls 4, a bottom 5, a frusto-conical top 6 and a suitable cork or closure 7. The inner

surface of the bottom, side walls and frusto-conical portions are coated with a layer of copper 8 (Fig. 3). In the present instance the bottom, side walls and frusto-conical portions each consist of a central iron sheet 9 and a coating 10 of tin on the outer or on 55 both sides thereof. The coating 8 of copper may be applied directly to the iron sheet 9 or to the inner coating of tin.

I have found that copper has no appreciable effect upon the qualities and properties of liquid orange shellac and similar substances, and it will be manifest therefore that a container or vessel embodying my invention may be used for an indefinite period to contain liquid orange shellac and the like 60 without producing the objectionable brownish color given the shellac when packaged in contact with tin. The copper coating may be applied either while the sheet metal is in uncut condition, while it is in the form of 65 blanks or after the container has been formed. An effective way of producing this internal copper surface is to provide the copper in the form of a thin sheet or foil and to roll it with the body of the sheet to 70 be used to form the container between heated metallic rolls so that the copper sheet or foil is substantially sweated or soldered to either a surface of the iron sheet or to one of the sheets of tin covering one of the surfaces of the iron sheet. It will be obvious 75 also that various changes may be made in the form, construction and arrangement of the parts without departing from the spirit and scope of the invention or sacrificing any 80 of its material advantages, the form hereinbefore described being merely a preferred 85 embodiment thereof.

I claim:

A commercial package comprising liquid 90 orange shellac or the like inclosed in a sheet metal vessel provided with a copper surface where the shellac comes in contact with the vessel.

BEN K. FORD.
